ELECTRIC HOT PLATE OR SIMILAR ARTICLE

Jerry E. Wright, 72 Catherine St., Corning, N.Y.

Filed Oct. 31, 1962, Ser. No. 72,329

Term of patent 14 years

(Cl. D81—10)

Fig. 1

Fig. 2

Fig. 3

FIG. 4

FIG. 1 is a top plan view of an electric hot plate or similar article embodying my new design.

FIG. 2 is a side elevation of the electric hot plate or similar article of FIG. 1. The opposite side not shown is substantially the same as the side shown in FIGURE 2.

FIGURE 3 is an end view taken from the left of FIGURE 1.

FIG. 4 is an end view taken from the right of FIG. 1.

I claim:

The ornamental design for an electric hot plate or similar article, as shown and described.

UNITED STATES PATENT OFFICE
CERTIFICATE OF CORRECTION

Design No. 196,951

November 19, 1963

Jerry E. Wright

It is hereby certified that error appears in the above numbered patent requiring correction and that the said Letters Patent should read as corrected below.

In the grant, lines 1 to 3, for "Jerry E. Wright, of Corning, New York," read -- Jerry E. Wright, of Corning, New York, assignor to Corning Glass Works, of Corning, New York, a corporation of New York, --; line 13, for "Jerry E. Wright, his heirs" read -- Corning Glass Works, its successors --; in the heading to the drawings and printed specification, line 3, for "Jerry E. Wright, 72 Catherine St., Corning, N. Y." read -- Jerry E. Wright, Corning, N. Y., assignor to Corning Glass Works, Corning N. Y., a corporation of New York --.

Signed and sealed this 19th day of May 1964.
